United States Patent Office

Des. 212,647
Patented Nov. 5, 1968

212,647

EYE TESTING UNIT

Harold Y. Minas, 2201 23rd Ave.,
Sacramento, Calif. 95822

Filed Oct. 13, 1967, Ser. No. 8,995

Term of patent 14 years

(Cl. D57—1)

FIG. 1

FIG. 2

FIG. 3

FIG. 4

FIG. 5

FIG. 1 is a perspective view of an eye testing unit showing my new design;

FIG. 2 is a side elevation view thereof, the opposite side is substantially the same in appearance as the sign shown;

FIG. 3 is a top plan view thereof;

FIG. 4 is a front view thereof; and

FIG. 5 is a bottom view of the eye testing unit.

I claim:

The ornamental design of an eye testing unit, as shown and described.
